DRIVE BUSHING FOR ROTARY TABLES

William H. Maxwell, Newport Beach, Calif., assignor to Baash-Ross Tool Company, Los Angeles, Calif., a corporation of California

Application August 8, 1938, Serial No. 223,577

10 Claims. (Cl. 255—23)

This invention relates to well drilling equipment and relates more particularly to bushings for use in the rotary tables of well drilling rigs. A general object of this invention is to provide 5 an improved drive or kelly bushing of the class embodying rollers for contacting the drive stem or kelly of a well drilling string.

In the rotary method of well drilling a rotary table is provided in the derrick to drive or rotate 10 the drilling tools. A drive stem or kelly or polygonal cross section is provided on the upper end of the well drilling string and a drive bushing is arranged in the rotary table to contact the kelly to transmit rotation from the rotary table to the 15 drilling string. The engagement of the bushing with the kelly is such that the kelly may be fed vertically while being rotated. Considerable friction and wear occur between the bushing in the rotary table and the kelly.

20 Drive bushings having rotatable rollers for engaging the faces of the kelly are used to reduce the wear and friction. The rollers of such bushings are usually supported to rotate about vertically spaced horizontal axes so that they contact the kelly at vertically spaced points. If the 25 spacing of the rollers is uniform the rollers have a tendency to track one after the other in engaging with the kelly, causing a series of impressions or corrugations to occur in the kelly. Continued engagement of the rollers in the corrugations 30 increases the corrugations causing material damage.

Another object of this invention is to provide a drive bushing for use in a rotary table that does 35 not groove, corrugate, or otherwise mar or distort the drive stem or kelly.

Another object of this invention is to provide a drive bushing embodying rotatable rollers for 40 contacting the drive stem or kelly that are arranged and related so that they cannot track one after the other in their engagement with the kelly and, therefore, do not form corrugations or 45 grooves in the kelly.

Another object of this invention is to provide a 50 drive bushing of the character mentioned in which the turning forces on the several faces of the polygonal kelly are maintained substantially equal so that the bushing has no tendency to bend or warp the kelly.

55 Another object of this invention is to provide a drive bushing of the character mentioned in which the rollers are arranged in vertical series and the adjacent rollers of each series are rotatable about non-parallel axes, so that they cannot track in their contact with the kelly faces.

Another object of this invention is to provide a drive bushing of the general character mentioned embodying novel means for mounting or supporting the kelly contacting rollers.

A further object of this invention is to provide 5 a bushing of the character mentioned in which the disposition or inclination of the rollers may be easily changed from time to time as conditions may warrant.

The various objects and features of my invention 10 will be fully understood from the following detailed description of a typical preferred form and application of the invention, throughout which description reference is made to the accompanying drawings, in which:

Fig. 1 is a side elevation of the improved bushing 15 of the present invention engaging about a drill stem or kelly and arranged in a typical rotary table, illustrating the rotary table in vertical cross section. Fig. 2 is a top or plan view of the bushing 20 arranged in the table, showing the kelly in horizontal cross section. Fig. 3 is an enlarged vertical detailed sectional view of the bushing removed from the table. Fig. 4 is a horizontal detailed sectional view taken as indicated by line 25 4—4 on Fig. 3. Fig. 5 is a top or plan view of one of the cages and its rollers removed from the bushing body and Fig. 6 is an enlarged vertical detailed sectional view taken as indicated by line 30 6—6 on Fig. 5.

The bushing structure of the present invention is intended primarily for use in the rotary table of a well drilling rig to engage and drive the drill 35 stem or kelly of the drilling string. In the drawings I have shown a typical preferred form of the invention used in a typical rotary table to drive a typical polygonal kelly. It is to be understood that the invention may be embodied in forms for use in other types of rotary tables and for cooperating with kellies of different cross 40 sectional configurations.

The typical well drilling equipment illustrated 45 in the drawings includes a rotary table T supported by bearings 10 to rotate about a vertical axis. The table T has a central vertical opening 11 receiving a master bushing 12. The master bushing 12 turns with the table and has a central vertical opening 13. The upper portion of the opening 13 is square or polygonal and the major portion of the opening 13 is tapered as clearly 50 illustrated in Fig. 1. A gear 14 meshes with teeth 15 on the under side of the table T to rotate the table. Figs. 1 and 2 of the drawings illustrate a typical kelly K of substantially square hori- 55

horizontal cross section extending vertically through the table T and its bushings.

The improved drive bushing of the present invention includes, generally, a body 16 for arrangement in the master bushing 12, cages 17 in the body 16, series or sets of rollers 18 in the cages 17 for contacting the kelly K and means 19 rotatably mounting or supporting the rollers 18 in the cages 17.

- 10 The body 16 is provided to contain the cages 17 and their rollers 18 and is shaped to be received in the opening 13 of the master bushing 12. The body 16 is a tubular member having a tapered lower portion 20 for fitting the tapered portion 15 of the opening 13 and having a square or polygonal portion 21 for fitting the square upper portion of the opening 13. The body 16 is of substantial length and projects upwardly beyond the upper surfaces of the master bushing 12 and the table T. A cylindrical externally threaded portion 22 is provided at the upper end of the body 16. The major portion of the opening in the tubular body 16 is generally square in horizontal cross section having four major walls 23. 20 The walls 23 are substantially vertical and the adjacent walls 23 are disposed at 90° to one another. Diagonal corner walls 24 extend between and connect the adjacent major walls 23. An inwardly projecting horizontal shelf or annular flange 25 is provided in the body 16 at the lower ends of its walls 23. The central opening 26 of the flange 25 is adapted to pass the enlarged end portions (not shown) of the kelly K with suitable clearance. 25 The cages 17 are frame-like parts provided to carry the rollers 18 and their mounting means 19. In the form of the invention illustrated there are four cages 17 fitted or arranged in the tubular body 16. The four cages 17 may be alike or identical and each includes two spaced vertical sides 27 and a bottom 28. A top 29 is provided for each cage 17 and is secured to the upper ends of its sides 27 by screws 30. The cages 17 are adapted to be inserted in the body 16 from its upper end 40 to have their bottoms 28 rest on the body flange 25. The outer surfaces of the cage sides 27 are adapted to engage against the main body walls 23. The diagonal corner walls 24 assist in locating the cages 17 in the body 16. The cages 17 preferably have interfitting or nesting portions to assist in holding them in place. The trailing side 45 27 of each cage 17, relative to the right hand direction of rotation, has a vertically extending notch or groove 31 in its inner portion receiving the inner corner portion of the advancing side 27 of the adjacent cage 17. The corner portions of the cages 17 fitting the grooves 31 assist in locating the cages in the body 16 and hold the cages against inward displacement and relative lateral shifting. 50

The rollers 18 are simple elongate roller elements having cylindrical external surfaces for contacting the flat vertical faces of the polygonal kelly K. The kelly contacting rollers 18 are tubular having central longitudinal openings 33. In accordance with the invention the several rollers 18 embodied in the bushing may be alike in size and shape. There is preferably a plurality of rollers 18 carried by each cage 17. In the form of the invention illustrated there are four rollers 18 carried by each cage 17. 65

The means 19 for mounting or supporting the rollers 18 in the cages 17 are important features of the invention. The means 19 support the rollers 18 in the cages 17 in such a manner that the

rollers cannot track one after the other in their engagement with the faces of the polygonal kelly K and, therefore, cannot groove or corrugate the kelly.

The roller supporting means 19 include supporting shafts or pins 34 for carrying the rotatable rollers 18. The pins 34 extend through the openings 33 of the rollers 18 and are sufficiently long to project beyond the opposite ends of the rollers. In practice the supporting pins 34 may be simple elongate members of uniform length. 5

The roller supporting means 19 further include blocks 35 arranged in the cages 17 to carry the projecting end portions of the pins 34. The blocks 35 are arranged in vertical grooves 36 in the inner surfaces of the cage sides 27. The grooves 36 extend downwardly from the upper ends of the cages 17 and terminate at or above the bottoms 28 of the cages. In the preferred construction the grooves 36 have flat vertical walls and 20 the two grooves 36 of each cage 17 are directly opposite one another. The supporting blocks 35 are proportioned to correctly fit the grooves 36 and are adapted to be introduced into the grooves at the upper ends of the cages 17. In the preferred construction the blocks 35 are alike in size and shape and are generally rectangular members. Where each cage 17 carries four rollers 18 there are four blocks 35 arranged in each groove 36. The blocks 35 are supported one upon 25 the other and the lowermost blocks 35 bear or rest on the bottom walls of the grooves 36. The blocks 35 are proportioned so that the tops of the uppermost blocks 35 are substantially flush with the upper surfaces of the cages 17. The tops 30 29 of the cages 17 may serve to retain the supporting blocks 35 in the cages. 35

Each block 35 has a transverse socket or opening 37 for receiving a projecting end portion of a roller supporting pin 34. The openings 37 are 40 preferably spaced midway between the upper and lower ends of their respective blocks 35. An inwardly projecting boss 38 is provided on the inner side of each block 35 around its opening 37. The disposition and relation of the openings 37 in 45 the pairs of horizontally opposing blocks 35 of a cage 17 are such that the pins 34 supported therein and the rollers 18 carried by the pins have non-parallel longitudinal axes. The openings 37 of each pair of horizontally aligned blocks 50 35 in a cage 17 may have an inclination or direction different from the openings 37 in the other sets or pairs of blocks in that cage 17. In the particular case illustrated in the drawings the lower blocks 35 of each cage 17 have horizontal 55 openings 37, the blocks 35 resting on the lower blocks 35 have openings 37 sloping in one direction, the third to the lowermost blocks 35 have openings 37 sloping in the other direction, and the uppermost blocks 35 have openings 37 sloping 60 in the same direction as the second to the lowermost blocks 35. The openings 37 that are inclined preferably have the same degree of inclination, and the blocks 35 provided with the inclined openings therefore may be identical. It 65 is to be understood that the lowermost blocks 35 of a cage 17 may have inclined openings 37 and if provided with such openings they may slope in the same direction as the openings 37 in the third to the lowermost blocks 35. It will be apparent that by inverting the blocks 35 the direction of inclination of their openings 37 may be reversed. 70

It is to be understood that the openings 37 of the blocks 35 in each cage 17 have their longi- 75

tudinal axes lying in a common vertical plane so that the rollers 18 supported on the pins 34 may all engage the opposing flat face of the polygonal kelly K. The active or inner faces of the bosses 38 are normal to the longitudinal axes of the openings 37 which they surround and serve to limit endwise movement of the rollers 18. As illustrated in the drawings the projecting end portions of the roller supporting pins 34 may be 10 directly carried in the openings 37 of the blocks 35.

From the above description of the relationship of the openings 37 in the stacked blocks 35 it will be seen that the rollers 18 are supported so 15 that the adjacent rollers of a series or set are rotatable about non-parallel or angularly related axes. In this connection it is to be understood that the rollers 18 preferably rotate on their pins 34 although, if desired, the pins 34 may rotate 20 in the openings 37 and the rollers 18 may be suitably fixed to the pins. The corresponding rollers 18 of the several cages 17 may rotate about axes having the same direction or inclination, or, if desired, the corresponding rollers 18 25 of the several cages 17 may be supported to rotate about axes having different directions or inclinations. As best illustrated in Fig. 4 of the drawings the rollers 18 supported as described above project inwardly from their cages 17 to 30 have their peripheries contact the flat faces of the kelly K for the transmission of turning forces to the kelly. It will be observed that the rollers 18 projecting from the inner sides of the cages 17 substantially define a square opening for receiving a square kelly.

The principal or heavy turning forces applied to the kelly K are transmitted to the forward corner portions of the kelly relative to the right-hand direction of rotation and it is preferred to 40 arrange the rollers 18 to project to or beyond the advancing forward corners of the kelly. As best illustrated in Fig. 4 of the drawings the rollers 18 are mounted in the cages 17 to have their transverse medial planes offset forwardly from 45 the central diametrical planes of the bushing body 16 with respect to the right-hand direction of rotation. This disposition or location of the rollers 18 provides for the projection of the rollers to or beyond the forward corners of the kelly 50 K assuming the kelly to be turning in a right-hand direction.

It is believed that it will be apparent how the blocks 35 may be assembled on the projecting end portions of the roller-supporting pins 34 55 and how the assemblies of the blocks, pins and rollers 18 may then be introduced in the cages 17. Following the arrangement of the rollers 18 and their supporting pins 34 and blocks 35 in a cage 60 17 the top 29 is secured to the cage and the cage is introduced in the bushing body 16. Tapered sockets 38 may be provided in the cage tops 29 to receive lifting tools (not shown) for facilitating the handling of the cages. When the several cages 17 have been arranged in the bushing body 65 16 a ring 39 is threaded on the upper portion 22 of the body 16. The ring 39 has an inwardly projecting annular flange 40 adapted to cooperate with the tops 29 of the cages 17 to hold the cages in position. The ring 39 preferably has projecting lugs 41 adapted to be brought in registration with similar lugs 42 on the bushing body 16. Bolts 43 are adapted to be passed through openings in the registering lugs 41 and 42 to 70 secure the ring 39 in place. If desired the ring 75

39 may be split at 44 and may be clamped onto the body portion 22 by a clamping screw 45.

It is believed that the use or operation of the improved kelly bushing of the present invention will be readily understood from the foregoing detailed description. Assuming that the body 16 is seated in the master bushing 12 and that the kelly K extends through the bushing, the engagement of the rollers 18 with the kelly provides for the transmission of rotation to the kelly. As the table T is rotated the rollers 18 engaging the flat faces of the polygonal kelly transmit the torque or turning forces to the kelly. The rollers 18 being independently rotatable allow the kelly K to move vertically as it is rotated. As described above, the rollers 18 of a vertical series or set in a cage 17 are related so that they cannot track one after the other in their engagement with the kelly K. Thus in the event that heavy turning forces cause one of the rollers 18 to make an impression in a face of the kelly K the adjacent roller 18 will not engage in this depression as the kelly is fed vertically. The rollers 18 being supported to rotate about angularly related axes cannot groove or corrugate the kelly K to any 25 substantial extent and, therefore, do not injure or cause warping of the kelly. The rollers 18 are supported in their cages 17 by simple, dependable means. The supporting blocks 35 and the pins 34 may be removed for replacement and, 30 if desired, or believed necessary, the blocks 35 may be inverted from time to time to change the angular disposition and relationship of the rollers 18.

Having described only a typical preferred form 35 and application of my invention I do not wish to be limited or restricted to the specific details herein set forth, but wish to reserve to myself any variations or modifications that may appear to those skilled in the art or fall within the scope 40 of the following claims.

Having described my invention, I claim:

1. A rotary table bushing for driving a polygonal kelly comprising a body to be carried by the table to rotate therewith and having an opening passing the drill stem, supporting cages in the body opening, vertically spaced rollers in each cage for contacting the kelly, and means supporting the rollers in the cages for rotation about angularly related axes, said means including supporting pins for the rollers, and block members in the cages having openings carrying the pins.

2. A rotary table bushing for driving a polygonal kelly comprising a body to be carried by the table to rotate therewith and having an opening passing the drill stem, supporting cages in the body opening, vertically spaced rollers in each cage for contacting the kelly, and means supporting the rollers in the cages for rotation about angularly related axes, said means including supporting pins for the rollers, and superimposed block members in the cages having openings carrying the pins, the openings in the adjacent block members being in angular relation.

3. A rotary table bushing for driving a polygonal kelly comprising a body to be carried by the table to rotate therewith and having an opening passing the drill stem, supporting cages in the body opening, vertically spaced rollers in each cage for contacting the kelly, and means supporting the rollers in the cages for rotation about angularly related axes, said means including supporting pins for the rollers projecting from the opposite ends of the rollers, and spaced stacks of

- blocks in the cages having openings carrying the projecting end portions of the pins, said openings in the adjacent blocks of the stacks being in angular relation.
5. A rotary table bushing for driving a polygonal kelly comprising a body to be carried by the table to rotate therewith and having an opening passing the drill stem, series of rollers for contacting the faces of the polygonal kelly for the transmission of turning forces to the kelly, supporting pins for the rollers projecting from their ends, and spaced rows of block members supported in the body and having openings carrying the projecting portions of said pins.
10. 5. A rotary table bushing for driving a polygonal kelly comprising a body to be carried by the table to rotate therewith and having an opening passing the drill stem, series of rollers for contacting the faces of the polygonal kelly for the transmission of turning forces to the kelly, supporting pins for the rollers projecting from their ends, and spaced rows of block members supported in the body and having openings carrying the projecting portions of said pins, said openings of the adjacent members of a row being in angular relation whereby the adjacent rollers of a series are rotatable about angularly related axes.
15. 6. A rotary table bushing for driving a polygonal kelly comprising a body to be carried by the table to rotate therewith and having an opening passing the drill stem, series of rollers for contacting the faces of the polygonal kelly for the transmission of turning forces to the kelly, supporting pins for the rollers projecting from their ends, and stacks of blocks supported in the body, said blocks having openings carrying the projecting end portions of the pins, the openings in the adjacent blocks of the stack being angularly related whereby the rollers are supported for rotation about non-parallel axes.
20. 7. A rotary table bushing for driving a polygonal kelly comprising a body to be carried by the table to rotate therewith and having an opening passing the drill stem, cages inserted in the body, each cage having spaced opposing grooves, rollers in the cages, supporting pins for the rollers projecting from their opposite ends, and blocks in the grooves having openings carrying the projecting end portions of the pins to support the rollers for engagement with the faces of the kelly.
25. 8. A bushing for use in a rotary table to drive a generally vertical drill stem comprising a body to be carried by the table and having an opening for passing the stem, a plurality of sets of rollers in the body for contacting the stem, and means supporting the several rollers of each of the said sets to have their axes of rotation parallel with a generally vertical plane and to extend transversely of the vertical axis of the stem in angular relation to one another whereby the lines of contact of their peripheries with the stem are non-parallel and one above the other.
30. 9. In combination with the body of a rotary table bushing, a plurality of rollers in the body for contacting a drill stem, the rollers being spaced one above the other, and means for supporting the rollers in the body for rotation about axes that are parallel with a generally vertical plane and that extend transversely of the vertical axis of the stem in angular relation to one another.
35. 10. A unit for use in the body of a rotary table bushing comprising a supporting cage, vertically spaced pins, rotatable rollers carried by the pins, and means mounting the pins in the cage to be parallel with a vertical plane and to extend transversely of a vertical axis in angular relation to one another whereby the lines of contact of the rollers with a vertical drill stem are vertically spaced and non-parallel.

WILLIAM H. MAXWELL.
